UNITED STATES PATENT OFFICE.

PATRICK FLEMING, OF NEW HAVEN, CONNECTICUT, ASSIGNOR TO HIMSELF AND WILLIAM M. FRISBIE, OF SAME PLACE

SASH-FASTENER.

SPECIFICATION forming part of Letters Patent No. 552,611, dated January 7, 1896.

Application filed November 6, 1894. Serial No. 528,043. (No model.)

To all whom it may concern:

Be it known that I, PATRICK FLEMING, a citizen of the United States, residing at New Haven, in the county of New Haven and State of Connecticut, have invented a certain new and useful Improvement in Sash-Fasteners, of which the following is a specification.

My improved fastener is of that class in which the sashes may be engaged together in a condition which holds the window partially open, so that both sashes may be raised together so as to present the ventilation aperture at the bottom, or both can be lowered together so as to present the ventilation aperture at the top, or both may be set in an intermediate position so as to divide the ventilation-aperture.

My invention comprises provisions whereby the part bolted on one sash partly embraces the part bolted on the other sash, so as to guide the parts as they slide one upon another in the first part of the opening and the last part of the closing movement, combined with means whereby the fastener may be adjusted to engage automatically when the sashes are brought into the closed position, or to avoid such engagement at will. It also allows the parts to be firmly held in the engaged position, so that the catch cannot be disengaged until the holding means shown as a flanged screw is relaxed. The sashes may be each approximately balanced by sash-weights in the ordinary manner.

The accompanying drawings form a part of this specification and represent what I consider the best means of carrying out the invention.

Figure 1 is a face view of a window provided with this invention. Figs. 2 and 3 represent portions on a larger scale. Fig. 2 is a perspective view, and Fig. 3 a vertical section.

All the figures show the window in the tightly-closed condition, but they indicate plainly the provisions for setting it open to five different degrees.

Similar letters of reference indicate corresponding parts in all the figures where they appear.

A is the upper sash and B the lower. These parts and the window-frame C, and other

parts not particularly represented, may be of any ordinary or suitable construction.

D is a plate screwed on the lower rail of the upper sash A. It supports a keeper D' of approximately semicylindrical section, having a series of recesses d in its plane face, adapted to receive a bolt or dog at different levels, as may become expedient, and to engage it strongly.

E is a casing screwed on the top rail of the lower sash B, and having arms E' E'', which partially embrace the keeper D', and serve to insure the proper relation of the parts D and E when the bolt is engaged. This casing E also contains a transverse way with a transverse slot in its top. The way receives a beveled ended bolt G, into which is tapped a milled headed screw H, which latter is inserted through the slot and traverses the slot as the bolt G, which may be termed also a "catch," is moved forward and backward by a force imparted by any means. The under face of the head H' is adapted to present a fair bearing on the upper face of the part E adjacent to the slot, when it becomes necessary to hold the bolt firmly in the engaged or disengaged position.

I is a spiral spring inclosed in a suitable recess. It exerts a force tending to throw the bevel-ended bolt G into engagement. This bolt is adapted to engage in any one of the recesses d to which it may be presented. It will be understood that the bolt is thrust outward by the spring I, and engages in the lowermost or in any other of the recesses d, according as the sash A is slightly elevated. To raise the lower sash the bolt G must be withdrawn against the tension of the spring I. This is easily effected by any person on the interior of the room, by grasping the head H' of the screw and drawing the bolt back thereby, the screw serving simply as a knob to effect this end.

Whenever the lower sash A is raised so that the bolt G is carried above the keeper D', it can be moved farther upward to any required extent, and may be lowered again without obstruction. When the sash is lowered so far relatively to the other, the upper sash, as to bring the parts of my device again into en-

gagement, the arms E' E² on the part E partially embrace the upright portion D' on the part D and insure the correct relation, and as the lower sash is moved downward the bevel-ended bolt G, which with its spring I behind it constitutes a spring-catch, is brought successively into coincidence with the several recesses d, and engages with each successively, until if the movement is continued sufficiently far the window is tightly closed and the spring-catch or bolt G is engaged in the lowermost of the recesses d, as shown.

It will be understood that if the catch is left engaged in one of the notches d above the lowermost the sash B can be depressed farther by a gentle force, the bevel end of the bolt receiving the contact in such manner as to force the bolt back, and it will promptly move out again under the influence of the spring.

By turning the screw II by means of its milled head II', so much friction can be applied to the bolt that it is tightly locked in position, and is incapable of being moved outward or inward. If this is done while the bolt is out, and engaging with either of the recesses d, it holds the window locked in that position. If a force is first applied to draw the bolt G back against the tension of the spring I, and then when it is fully back the screw is turned so as to tighten its hold, it will under those conditions lock the bolt in the unfastened or ineffective position. When my fastener is thus adjusted, the window may be raised and lowered in the ordinary manner. This condition may be induced temporarily in certain windows which may require to be opened often at certain times.

The engagement of the part D' by the arms E' E² insures that the sashes shall be exactly in line, and that the parts D and E shall be in close contact when the sashes are in position for being fastened. This gives certainty of operation in engaging and disengaging even if the sashes have through age and shrinkage or other fault become loose in other places. This is also an advantage when the sashes are closed in cold weather in insuring that the joint shall be close between the upper and lower sashes.

While the details of construction shown in the drawings are the ones I prefer, they are subject to modifications which would not depart from the spirit of the invention, and are intended to be included by the claims. The

length of the part D, which I term a "keeper" and which receives and engages the bolt G at different heights, may be greater or less than shown. The upper end of the keeper may be less beveled than shown.

Parts of the invention can be used without the whole. I can realize some of the advantages by the use of other forms of head to the screw II or by using a simple knob properly attached in place of the screw. In such case I lose the capacity of fastening the bolt.

Instead of placing the fastening in the mid-width of the window, as shown, it may be placed at either side. Two may be used, one on each side of a wide window.

I claim as my invention—

1. In a window fastener a self-acting spring catch on one sash in combination with a keeper on the other sash, such keeper having a number of recesses at different elevations so as to allow the window to be fastened in a slightly opened condition and to allow both sashes to be raised and lowered together to present the opening for ventilation at the top or bottom at will; and with the arms E', E², on one part partially embracing the upright keeper D' on the other part so as to insure the correct relation of the parts when the catch is engaged, all substantially as herein specified.

2. In a window fastener a self acting spring catch on one sash in combination with a keeper on the other sash having a number of recesses at different elevations so as to allow the window to be fastened in a variably open condition and to allow both sashes to be raised and lowered together to present the variable opening for ventilation at the top or bottom at will and with the arms E' E² on one sash partially embracing an upright guide on the other sash so as to insure the correct relation of the parts horizontally and with the fastening screw II arranged to hold the catch firmly in either the locked or unlocked condition at will or to leave the catch free to be shifted as required all substantially as herein shown and described.

In testimony that I claim the invention above set forth I affix my signature in presence of two witnesses.

PATRICK FLEMING.
